ELECTRONIC AMPLIFIERS

Hendrikus Theodorus Joseph Wiegerinck, Cambridge, England, assignor to Pye Limited, Cambridge, England, a British company

Application May 26, 1952, Serial No. 290,002

Claims priority, application Great Britain June 1, 1951

7 Claims. (Cl. 258—27)

The present invention relates to electronic amplifiers and more particularly to radio receivers which may be operated either from the supply mains or batteries, and are of the kind which comprise a number of filamentary type electron tubes, including a filamentary type output tube which is used as the output tube during operation from the batteries, and an indirectly-heated cathode type output tube which is used as the output tube during operation from the supply mains and has its heater supplied by the supply mains, and in which during operation from the supply mains the filament current for the filamentary type electron tubes is derived from the H. T. supply through the cathode type output tube and during operation from the batteries the filament current of all the tubes which are then in operation is supplied from batteries.

Known receiver arrangements of this kind suffer from the disadvantage, when operating from the supply mains, that fluctuations in the supply mains voltage causes variations in the current through the cathode type output tube and hence variations in the filament current of the filamentary type electron tubes fed therefrom. Since the filament current for the filamentary type electron tubes, which are of the directly-heated type, should be kept constant within small limits to avoid damage to the tubes, these filament current variations, particularly if they cause an increase over the rated filament current for a tube tend to shorten the life of the filament, or if the increase is sufficiently great the filament or filaments will burn out. Conversely if the variations cause a reduction in the filament current to below the rated value, a deterioration of the performance of the receiver will result. Variations in filament current may also occur if the cathode type output tube has to be replaced, since small differences in characteristics may occur between different tubes of the same type.

It is an object of the present invention to overcome this disadvantage and provide an arrangement whereby when operating from the supply mains the filament current of the filamentary type electron tubes may be kept substantially constant and independent of fluctuations in the supply mains voltage.

To this end, according to the present invention, in an electronic amplifier and more particularly a radio receiver of the kind described, a D. C. connection is provided between a grid of the cathode type output tube and a load connected in series with a preceding valve, when operating from the supply mains, whereby a D. C. bias voltage developed across said load may be applied to the cathode type output tube to control its conductance to compensate for fluctuations of the supply voltage and so that the filament current supplied to the filamentary type electron tubes through said cathode type output tube remains substantially constant.

Preferably, the D. C. connection is made between the signal grid of the cathode type output tube and the anode of the preceding tube, which is normally acting as an L. F. amplifier stage, the D. C. voltage being developed across the anode load of the preceding tube and serving

2

as a bias voltage on the signal grid of the cathode type output tube to control the current flow therethrough. For operation from batteries, the connection from the anode of the preceding L. F. amplifier to the grid of the filamentary type output tube, which is then in use, is made through a condenser.

Preferably the filamentary type electron tubes have their filaments connected in series in such a manner that the filament of any filamentary type electron tube which is not in use when operating from the supply mains, for example the filamentary type output tube, may be switched out of circuit.

In a preferred form of the invention, the series connected filaments draw their current supply from the cathode type output tube through a resistor connected in series with the cathode of that tube, this resistor being preferably of the type having non-linear characteristic which further assists in maintaining the filament current to the remaining filamentary type electron tubes at the correct value. If desired this resistor may be made variable or be pre-set to facilitate in the initial adjustment of the filament current. For this resistor, the heater of the cathode type output tube could be used in some applications. A large condenser is connected across the resistor and series connected filaments to filter out audio frequency variations in the cathode current of the cathode type output tube.

In order that the invention may be more fully understood, reference will now be made to the accompanying drawing which shows the basic circuit arrangement of a radio receiver constructed in accordance with this invention.

This receiver is constructed with filamentary type electron tubes V₁, V₂, V₃, and V₄, having their filaments connected in series. During operation from batteries the filaments of these tubes are supplied from the battery B. The tube V₄ represents the filamentary-type output tube and tube V₃ is a low-frequency amplifier feeding this valve. Tubes V₁ and V₂ represent preceding stages in the receiver. An indirectly heated cathode type output valve V₅ is also provided which fulfils the function of the filamentary type output valve V₄ during operation from the supply mains, when the filament of the filamentary type output tube V₄ is switched out of circuit by the switch S₄. The anode of the tube V₃ is connected through a resistor R₃, to the signal input grid of the tube V₅ which is in use when operating from the supply mains, and is also connected through the condenser C₃ to the signal input grid of the tube V₄ which is in use when operating from batteries. The filament h of the tube V₅ is supplied from the supply mains and the filaments of the remaining tubes V₁, V₂ and V₃, when operating from the supply mains, are connected between the cathode of the tube V₅ and the H. T. negative line and supplied with current derived from the cathode high tension supply through the mains type output tube V₅ in a known manner. A nonlinear resistor R₁ is connected in series with the cathode of the cathode type output tube V₅ and the filaments of the battery type tubes V₁, V₂ and V₃, to provide the appropriate negative grid bias for the tube V₅. A large condenser C₁ is connected from the cathode of tube V₅ across the resistor R₁ and the series connected filaments of tubes V₁, V₂ and V₃ to by-pass the audio frequency variations in the current of the cathode type output tube V₅, and the current fed through the resistor R₁ to the filaments of tubes V₁, V₂ and V₃ is therefore substantially free from A. C. components. The screen grid of the tube V₃ is fed from a tapping point on the resistor R₁, during operation from the supply mains, which tends to improve the power regulation, and during operation from batteries the screen grid of this tube is fed

through the resistor R_2 connected to the positive H. T. supply line from the H. T. battery, the connection to the resistor R_1 being broken by the switch S_3 . During operation from the supply mains, the H. T. supply for the tubes V_1 and V_2 is derived from the junction of the resistor R_1 and the cathode of the tube V_5 and during operation from batteries the H. T. supply to these tubes is derived through the dropping resistor R_4 . This change-over is effected by the switches S_5 and S_6 . The tubes V_3 and V_4 , or V_3 and V_5 are supplied from the battery or mains H. T. supply respectively by suitable operation of the switches S_1 , S_2 and S_6 .

The various switches shown form different sections of a multi-polar switch, operated by a single control, the arrangement being such that during operation from batteries the switches S_2 , S_4 and S_6 are closed and the switches S_1 , S_3 and S_5 are open. For operation from the supply mains, as shown in the drawing the switches S_2 , S_4 and S_6 are open; and the switches S_1 , S_3 and S_5 are closed.

The action of the bias circuit will now be explained. During operation from the supply mains, an increase in current through the tube V_5 due to an increase in supply voltage tends to cause an increase in heater current through the preceding tubes V_1 , V_2 and V_3 , which are filamentary type electron tubes and thereby cause the filament emission of these tubes to increase. This increased filament emission causes the tube current to rise and in the case of the tube V_3 produces a greater voltage drop across the load resistor R_5 connected in series with the anode of this tube. Since the anode of the tube V_3 is directly coupled to the signal input grid of the output tube V_5 , the voltage across the resistor R_5 is applied as a bias to the signal input grid of the tube V_5 , and the increased voltage drop across resistor R_5 therefore increases the bias applied to the grid of the tube V_5 and tends to decrease the current flowing therethrough and thereby maintains the filament current flowing through the preceding filamentary type electron tubes V_1 , V_2 and V_3 at its correct value. Conversely if the current through the cathode type output tube V_5 decreases from its normal value, due to fluctuation in the supply voltage, the emission of the tubes V_1 , V_2 and V_3 tends to decrease, reducing the tube current and hence the voltage dropped across the load resistor R_5 . This decreases the bias applied to the signal input grid of the tube V_5 and allows this tube to draw more current, thus again maintaining the filament current of the battery type tubes V_1 , V_2 , V_3 at the correct value.

The cathode potential of the tube V_5 is arranged to be of such a value that although the signal grid of this tube is connected to the H. T. supply through the resistor R_5 no grid current normally flows in the tube V_5 and the tube is able to operate as an output tube working on the normal part of its characteristic. This cathode potential is determined by the value of the resistor R_1 , and the voltage drop across the heaters of the tubes V_1 , V_2 and V_3 .

It will be understood that only the basic circuit arrangement has been described, and that other switches will be provided to switch the circuit connections between the electrodes of tube V_4 and tube V_5 when changing from battery operations to mains operation and vice versa.

Whilst a particular embodiment has been described, it will be understood that various modifications may be made without departing from the scope of the invention. For example the bias voltage may be derived from an earlier stage in the receiver or amplifier, instead of from the L. F. amplifier feeding the output tube as above described.

In a further modification the bias voltage may control the conductance of the cathode-type electron tube by applying this voltage to the suppresser grid instead of to the signal input grid.

I claim:

1. Electronic apparatus which may be operated from

supply mains and batteries, comprising a plurality of filamentary type electron tubes, and a cathode type electron tube having a heater, a cathode and at least one grid electrode, and having its heater supplied from the

5 supply mains, a battery for supplying filament current to said filamentary type electron tubes during operation from batteries, a source of high tension voltage for said filamentary type electron tubes during operation from batteries, a source of high tension voltage for said tubes 10 during operation from supply mains, means connecting the filaments of at least some of said filamentary type electron tubes in series with the cathode of said cathode type electron tube during operation from the supply mains, whereby the filaments of said filamentary type electron tubes are supplied from the current flowing through said 15 cathode type tube, a resistive load connected in series with the anode of one of said filamentary type electron tubes and a direct current connection between said resistive load and a grid of said cathode type electron tube during operation from supply mains.

2. Electronic apparatus which may be operated from supply mains and batteries, comprising a plurality of filamentary type electron tubes, and a cathode type electron tube having a heater, a cathode, and at least one grid electrode, and having its heater supplied from the 20 supply mains, a battery for supplying filament current to said filamentary type electron tubes during operation from batteries, a source of high tension voltage for said filamentary type electron tubes during operation from batteries, a source of high tension voltage for said tubes 25 during operation from supply mains, means connecting the filaments of at least some of said filamentary type electron tubes in series with the cathodes of said cathode type electron tube during operation from the supply mains, whereby the filaments of said filamentary type electron tubes are supplied from the current flowing through said cathode type electron tube, a resistive load connected in series with one of said filamentary type electron tubes and a direct current connection between said resistive load and a grid of said cathode type electron tube during operation from supply mains.

3. Electronic apparatus which may be operated from supply mains and batteries, comprising a plurality of filamentary type electron tubes, at least one of said filamentary type electron tubes having a screen grid, and a cathode type electron tube having a heater, a cathode, and at least one grid electrode and having its heater supplied from the supply mains, a battery for supplying filament current to said filamentary type electron tubes during

30 operation from batteries, a source of high tension voltage for said filamentary type electron tubes during operation from batteries, a source of high tension voltage for said tubes during operation from supply mains, means connecting the filaments of at least some of said filamentary type electron tubes in series with the cathode of said cathode type electron tube during operation from the supply mains, whereby the filaments of said filamentary type electron tubes are supplied from the current flowing through said cathode type electron tube, a resistive load connected in series with a filamentary type electron tube having a screen grid, a direct current connection between said resistive load and a grid of said cathode type electron tube during operation from supply mains and a direct current connection between the cathode of said cathode type electron tube and the screen grid of the said filamentary type electron tube in series with said resistive load.

4. Electronic apparatus which may be operated from supply mains and batteries, comprising a plurality of filamentary type electron tubes, at least one of said filamentary type electron tubes having a screen grid, and a cathode type electron tube having a heater, a cathode, and at least one grid electrode and having its heater supplied from the supply mains, a battery for supplying filament current to said filamentary type electron tubes dur-

70 75

ing operation from batteries, a source of high tension voltage for said filamentary type electron tubes during operation from batteries, a source of high tension voltage for said tubes during operation from supply mains, means connecting the filaments of at least some of said filamentary type electron tubes in series with the cathode of said cathode type electron tube during operation from the supply mains, whereby the filaments of said filamentary type electron tubes are supplied from the current flowing through said cathode type electron tube, a resistive load connected in series between the anode of a filamentary type electron tube having a screen grid and the high tension positive supply line, a direct current connection between the anode of said filamentary type electron tube having a screen grid and a grid of said cathode type electron tube during operation from supply mains, and a resistor connected between the cathode of said cathode type electron tube and the screen grid of said filamentary type electron tube which is in series with the resistive load.

5. Electronic apparatus which may be operated from supply mains and batteries, comprising a plurality of filamentary type electron tubes, at least one of said filamentary type electron tubes having a screen grid, and including a filamentary type output tube having at least one grid electrode, and used as an output tube during operation from batteries and a cathode type electron tube having a heater, a cathode, and at least one grid electrode and having its heater supplied from the supply mains, and used as an output tube during operation from the supply mains, a battery for supplying filament current to said filamentary type electron tubes during operation from batteries, a source of high tension voltage for said filamentary type electron tubes during operation from batteries, a source of high tension voltage for said tubes during operation from supply mains, means connecting the filaments of at least some of said filamentary type electron tubes in series with the cathode of said cathode type electron tube during operation from the supply mains, whereby the filaments of said filamentary type electron tubes are supplied from the current flowing through said cathode type electron tube, a resistive load connected in series between the anode of a filamentary type electron tube having a screen grid and the high tension positive supply line, a direct current connection between the anode of the said filamentary type electron tube having a screen grid and a grid of said cathode type electron tube and a non-linear resistor, between the cathode of said cathode type electron tube and the screen grid of the said filamentary type electron tube in series with the resistive load.

6. Radio receiving apparatus which may be operated from supply mains and batteries, comprising a plurality of filamentary type electron tubes, including a filamentary type output tube used as an output tube during operation from batteries and a cathode type electron tube having a heater, a cathode, and at least one grid electrode and having its heater supplied from the supply mains, and used

as an output tube during operation from the supply mains, a battery for supplying filament current to said filamentary type electron tubes during operation from batteries, a source of high tension voltage for said filamentary type electron tubes during operation from batteries, a source of high tension voltage for said tubes during operation from supply mains, means connecting the filaments of at least some of said filamentary type electron tubes in series with the cathode of said cathode type electron tube during operation from the supply mains, whereby the filaments of said filamentary type electron tubes are supplied from the current flowing through said cathode type electron tube, a resistive load connected in series with one of said filamentary type electron tubes and a direct current connection between said resistive load and a grid of said cathode type electron tube during operation from supply mains.

7. Radio receiving apparatus which may be operated from supply mains and batteries, comprising a plurality of filamentary type electron tubes, at least one of said tubes having a screen grid and including a filamentary type output tube used as an output tube during operation from batteries and a cathode type electron tube having a heater, a cathode, and at least one grid electrode and having its heater supplied from the supply mains, and used as an output tube during operation from the supply mains, a battery for supplying filament current to said filamentary type electron tubes during operation from batteries, a source of high tension voltage for said filamentary type electron tubes during operation from batteries, a source of high tension voltage for said tubes during operation from supply mains, means connecting the filaments of at least some of said filamentary type electron tubes in series with the cathode of said cathode type electron tube during operation from the supply mains, whereby the filaments of said filamentary type electron tubes are supplied from the current flowing through said cathode type electron tube, a resistive load connected in series between the anode of a filamentary type electron tube having a screen grid and the high tension positive supply line, a direct current connection between the anode of the said filamentary type electron tube having a screen grid and a grid of said cathode type electron tube, and a non-linear resistor connected between the cathode of said cathode type electron tube and said screen grid of the said filamentary type electron tube in series with the resistive load.
